UNITED STATES PATENT OFFICE.

THEODORE H. WITTLIFF, OF CLEVELAND, OHIO.

FURNITURE BRACE.

Application filed May 3, 1926. Serial No. 106,192.

This invention as indicated relates to a furniture brace. More particularly it includes a furniture brace adapted to secure to an intermediate body portion, members 5 extending at an angle with respect thereto. The device is especially useful in securing the back frame and the leg section of a chair to the seat portion thereof.

In copending applications, (Serial No. 25,341, filed April 23, 1925, and Serial No. 25,342, filed April 23, 1925), I have illustrated a number of methods of securing the leg portions of a chair or similar article of furniture to the body portion thereof, but 15 in such disclosures, no cooperation with a securing member for an upwardly projecting frame structure was set forth. In the present invention several constructions combining a leg tensioning device with a back 20 tensioning device are illustrated, but it is to be understood that the forms shown are not to be regarded as in any way limiting the character of the leg portion of the device but that I may use features of the leg braces 25 heretofore illustrated in so far as may be found desirable in combination with a back brace as herein claimed.

In large industrial establishments, particularly in garment factories and the like, 30 wherein operators at sewing machines require chairs in their daily work, it is found that such chairs are moved about the floor and subjected to various stresses and rapidly develop lost motion in both the leg sections 35 and back sections. It entails considerable expense to maintain the chairs in a safe condition for use and many replacements are necessary. As a means for improving the seating units for such establishments, it has 40 been attempted to provide integral metal chairs, but such equipment is expensive and cannot be as readily repaired as wooden chairs. Furthermore, it is heavier and not as acceptable to the workers as the standard 45 wooden chairs heretofore used. To a certain extent it has been the practice to string wires across the leg sections of the wooden chairs, but no takeup means has heretofore been provided and the wires soon become of 50 no effect.

The principal object of the present invention is to provide a bracing means for standard wooden chairs which will prevent the development of lost motion in either the back or leg portions thereof and which by

means of a wrench or similar device may be tensioned from time to time to maintain the seating equipment in satisfactorily rigid condition.

Another object of my invention is to provide a simple bracing means which may be applied to chairs now in use or which may be supplied to furniture manufacturers at small expense, for original equipment, and which will serve to draw the back and leg 60 portions of the chair toward the seat portion thereof. Another object of the invention is to provide a furniture brace which may be readily adjusted as required when the glue or other fastening means used in 65 the manufacturing of such furniture dries out and the parts develop lost motion and the structure becomes unsafe or unsatisfactory for use. A further object of the invention is to provide simple and improved 70 parts for coacting with flexible tensioning elements to hold the upper and also the lower frame portions of a chair or other article of furniture in rigid relation to each 75 other. Other and further objects of the invention will appear in the course of the following description. To the accomplishment 80 of the foregoing and related ends, said invention, then consists of the means hereinafter fully described and particularly 85 pointed out in the claims.

The annexed drawing and the following description set forth in detail certain mechanism embodying the invention, such disclosed means constituting, however, but one 90 of various mechanical forms in which the principle of the invention may be used.

In said annexed drawing:

Fig. 1 is a rear elevation of a chair equipped with bracing means embodying 95 the principles of my invention; Fig. 2 is a side elevation of a chair similar to that shown in Fig. 1; Fig. 3 is a plan view partly in section, of the seat portion of the chair illustrated in Fig. 2, taken along the line 100 3-3 shown in Fig. 2, looking in the direction of the arrows; Fig. 4 is a view in enlarged perspective, showing the guide and securing plate and the tensioning device illustrated in Figs. 1, 2 and 3; Fig. 5 is a 105 plan view of a plate showing a modified form of attaching the flexible members; Fig. 6 is an enlarged vertical sectional view showing the method of fastening my preferred form of plate to the under side of 110

the seat of a chair; Figs. 7 and 8 are modified forms of tensioning bolts adapted for use with the several forms of furniture braces illustrated; and Fig. 9 is a fragmentary perspective view showing a tensioning plate wherein flexible straps are used in place of flexible cables.

As clearly shown in Figs. 1 and 2 of the drawing, my preferred form of chair brace 10 is applied to a standard wooden seat chair having a heavy seat portion 1, at the rearward upper side of which a bow-shaped back member 2 is mounted in sockets formed in the upper portion of said seat and a plurality 15 of spindles 3 are engaged at their respective ends within sockets formed in said bow-shaped member and seat portion respectively. The seat is supported upon legs 4 engaged in sockets adjacent the respective corners of the seat on its under side. Said legs are provided with the usual cross braces 5 engaged at their respective ends in sockets at a point adjacent the central portion of such legs.

25 The bow-shaped member of the back is provided at spaced points, preferably slightly outside of the outer spindles, with a pair of apertures 6, 7, to receive a flexible member 8, such as a wire which is 30 adapted to lie on the upper face of said bow-shaped member or to be received in a groove formed in said upper face. The respective ends of said wire extend downwardly through spaced apertures 9, 10, in 35 the bottom of said seat, at a point preferably in lateral alignment with said spindles, and their free ends are secured to the bottom of the seat at a central point by means of a fastening plate 11. The fastening plate as 40 is more clearly shown in Fig. 4 of the drawing has four screw holes 12, and a longitudinally extending channelway 13 provided by displacing the metal downwardly upon the central line thereof. Said channelway 45 is of a size to receive and frictionally engage the ends of the flexible member as is shown in Fig. 6. The extreme ends 14 of said flexible member project from the plate and are turned downwardly in the manner shown in Fig. 4 to further prevent the withdrawal of said member from beneath said plate when tension is applied to an adjacent part of said flexible member. The plate is formed at one end with an extension 55 15 at right angles to the body portion and has a slot 16 through which intermediate portions of the flexible member are engaged thus forming a pair of loops 17 in the manner clearly shown in Fig. 4.

60 A pair of flexible members 18 formed of wire or equivalent material are connected with opposite pairs of legs of the chair either by forming loops 19 on the ends of said wires adapted to engage hooks 20 fastened in said legs at the inner sides thereof,

or provided with large loops at their ends in the manner of the strap illustrated in Fig. 9 which loops are of a size to engage over the bottom ends of the legs and slide upwardly thereon until stopped by a cross-member or by a snug fit with the tapered lower portion of the respective legs. The flexible members connected with the legs have their central portions engaged over a plate 21 having its ends 22 turned upwardly to receive the same. The plate is provided with a central aperture 23 adapted to permit the passage of the shank of a tensioning bolt 24.

70 The bolt in the preferred form of construction is provided with a head 25 which bears against a plate 26 similar to that just described which is centrally apertured and has downwardly turned portions 27 which engage over the loop sections 17 of 85 the upper bracing member heretofore described. A nut 28 is secured to the screw-threaded end of the bolt and by adjusting said nut by means of a suitable wrench any desired degree of tension may be applied 90 to the respective flexible members.

95 In place of the standard bolt having a head, of a type just described, a bolt 31 having an elongated head 32 provided with a pair of parallel apertures 33, as is shown in Fig. 7, may be used. Or a bolt 34 having an upper terminal of the character shown in Fig. 8 may be used wherein oppositely directed hooks 35 are formed at one end.

100 In place of wires or cables, it may be found desirable to employ metal straps 41 of the character illustrated in Fig. 9. Such straps are preferably formed of light strip metal engaged through slots 42 angularly disposed adjacent each of the cut-away corners of a lower tensioning plate and have a loop 43 adapted to extend about the lower portion of the leg of the chair. Similar straps may be applied to the bow-member of the back of a chair, the loops being adapted 105 to extend about the bow member preferably just inside of the outer spindles and the straps passing downwardly and through side slots at the bottom of the chair.

110 Instead of using a fastening and guide plate of the type shown in Fig. 4, I may provide a plate 51 of the character illustrated in Fig. 5, wherein the central longitudinal channelway is dispensed with and a pair of diverging grooves 52 terminating 115 short slots 53 are formed adjacent one end. The respective end portions of the flexible member 8 are laid in said grooves and the extreme ends of said member are engaged through the slots and bent to form hooks 54 120 which assist in preventing said end portions being withdrawn under tension.

125 While the drawings and description have specifically set forth only a chair construction it is to be understood that it is not in- 130

tended thereby to in any way restrict the invention to use with that particular article of furniture, as substantially the same braces may be used to make more rigid the mirror supports and legs of a dressing table, and various other articles of furniture may be similarly braced.

Other modes of applying the principle of my invention may be employed instead of 10 the one explained, change being made as regards the mechanism herein disclosed, provided the means stated by any of the following claims or the equivalent of such stated means be employed.

15 I therefore particularly point out and distinctly claim as my invention:

1. In an article of the character described, the combination of a body portion, an upwardly extending back bow and frame structure 20 associated with said body portion, a downwardly extending frame structure associated with said body portion, bracing means in the form of a closed loop connecting said upper frame structure with said body portion, and engaged above and looped through said back bow and secured to said body and providing a pair of tensioning

portions beneath said body; bracing means attached to said downwardly extending frame structure and means adapted to simultaneously apply tension to each of said 30 bracing means beneath said body portion.

2. A chair having a solid seat provided with sockets in the upper and lower sides thereof, a back member mounted in the 35 sockets on the upper side of said seat, leg members mounted in the sockets on the lower side of said seat, a combined guide and fastening member secured to the under side of said seat, a flexible bracing device 40 engaged with said back member and with said guide and fastening member, flexible bracing members connected at points spaced from said seat with the respective leg members and a tensioning member slidably engaged 45 with a portion of said back bracing member adjacent said guide and fastening member and with the flexible bracing members for said leg members to simultaneously draw said back member and said leg members 50 toward said seat.

Signed by me this 16th day of April, 1926.

THEODORE H. WITTLIFF.
